UNITED STATES PATENT OFFICE

JOHN P. DORAU, OF HORICON, WISCONSIN

FOLDING IRONING TABLE

Application filed August 22, 1927. Serial No. 214,630.

This invention relates to improvements in folding ironing tables.

It is one of the objects of the present invention to provide an ironing table which may be easily and quickly folded to a closed position, in which position the table is compact for storing.

A further object of the invention is to provide a folding ironing table having a foot latch operable to unlock the table legs for folding.

A further object of the invention is to provide a folding ironing table in which the supporting legs may be securely locked in open position, so that they cannot accidentally close or provide an unsteady support.

A further object of the invention is to provide a folding ironing table equipped with three legs all operatively connected together so that a movement of one leg will tend to move the others also.

A further object of the invention is to provide a folding ironing table having braces adapted to engage some of the legs in open position, causing a divergence of the same to provide a steady support.

A further object of the invention is to provide a folding ironing table which is of simple construction, is strong and durable, is inexpensive to manufacture, and is well adapted for the purpose described.

With the above and other objects in view the invention consists of the improved folding ironing table and its parts and combinations as set forth in the claims, and all equivalents thereof.

In the accompanying drawing in which the same reference characters indicate the same parts in all of the views:

Fig. 1 is a side view of the ironing table in open position;

Fig. 2 is an inverted plan view thereof with the parts in folded position;

Fig. 3 is an end view of the table in open position; and

Fig. 4 is an end view of a modified form of ironing table.

Referring now more particularly to the drawings, it will appear that the numeral 8 indicates the ironing board or table proper,

which may be of any suitable shape, but is preferably of rectangular form, except the front portion 8' which is tapered. A U-bracket 9 is secured to the undersurface of the board medially of its ends and another bracket 10 is secured to the undersurface of one end portion of the board.

Pivots secured to the end portions of the bracket 10 are a pair of downwardly diverging legs 11. The bracket 10 is formed with an intermediate U-portion 10' and pivotally secured to said portion is a small U-bracket 12 to one side of which the upper end portions of a pair of diverging braces 13 are secured. The lower end portions of said braces are secured to the lower end portions of the legs 11, as clearly shown in Fig. 3.

A long leg 14 has its upper end portion pivotally secured within the U-portion 10' of the bracket 10 and said leg is slightly flexible and extends toward the end 8' of the board 8.

The upper end portions of a pair of downwardly and outwardly diverging braces 15 are pivotally secured to the end portions of the bracket 9 and the upper end portions of said braces are cut angularly, as at 15', to bear against the undersurface of the board 8 when the table is unfolded. Each of said braces 15 has pivotally secured to an intermediate portion one end portion of a link 16. The other end portions of said links are pivotally secured to lower portions of the legs 11.

As a connection between the leg 14 and the braces 15 a V-shaped locking member 17 is provided and the free end portions of the same have a hooked engagement with staples 18 depending from outer end portions of the braces 15. The mid-portion of said member 17 is looped, as at 19, with a lower cross bar 20. The outer end portion of the leg 14 is extended through said looped portion 19 and is slidable with respect thereto and is formed with a notch 21 for releasable locking engagement with the cross bar 20.

The lower end portions of the braces 13 are provided with notches 22 which engage the outer end portions of the braces 15 when the table is in open position. Also, the elongated

leg 14, intermediate its ends, carries a transverse member 23 having reduced end portions 23' adapted to move along the surfaces of the braces 15 when the parts are being unfolded, exerting an outward pressure on the same, and being limited by pins 24.

When the table is folded the parts are as shown in Fig. 2, lying length-wise against the undersurface of the board 8. To unfold the table, the legs 11 are moved away from the board and the braces 13 will move therewith. Also, the elongated leg 14 is moved away from the board and when the transverse member 23 engages the braces 15 it will 10 exert a pressure thereon to force the lower end portions of said braces into the notches 22 of the braces 13. In this manner the legs 11 and braces 13 are held very firmly under pressure in a diverged position. While the 20 leg 14 is being moved outwardly, it moves through the looped portion 19 of the locking member 17 and to lock the leg 14 and all of the parts in open position the leg 14 is moved until the notch 21 is adjacent the bar 20 of the member 17 and then said leg may be 30 flexed a trifle to snap the bar into said notch. In this way all of the parts are held rigidly and under tension in open position. As the ends of the member 17 are connected to the braces 15, the same are held in their open 40 positions in engagement with the notched portions of the braces 13. In folding or closing the ironing table it is only necessary to press on the upper part of the looped portion 35 of the locking member to disengage it from the notch 21 and then all of the legs and braces may be folded against the board.

In Fig. 4 a slightly modified form of ironing board is shown wherein one end portion 40 of the board is provided with a pair of brackets 25 spaced from the undersurface of the board by a block 26. The braces 13 are pivotally secured to the inner ends of the brackets 25 and between the same the upper end portion of the leg 14 is pivotally mounted. The legs 11 are pivotally connected to the outer end portions of the brackets 25. The end portions of a flexible member or chain 27 are connected to intermediate portions of the braces 15 and an intermediate portion of said chain is secured to the leg 14. Said chain permits folding of the parts as well as causing a unity of movement between the leg 14 and braces 15 and when the parts 55 are unfolded, as in Fig. 4, the chain is stretched taut.

From the foregoing description it will be seen that the improved folding ironing table is of very simple and novel construction, and is well adapted for the purpose described.

What I claim as my invention is:

1. An ironing table, comprising a board member, a pair of legs and a third leg pivotally connected to the bottom portion of the board near one end portion thereof and mov-

able away from the board to extended diverged positions, a pair of brace members pivotally connected at one pair of ends to the bottom portion of the board medially of its ends, the other ends of said brace members being free, said brace members and said third leg crossing each other medially of their lengths when moved away from the board, the outer end portions of said braces releasably bearing against the inner sides of said pair of legs and exerting a lateral pressure thereon, links pivotally connected with said braces and said pair of legs, means connected with the links and releasably engageable with the third leg to hold it in open position and slidably thereon, and means carried by the third leg and engageable with said brace members to hold the same in open position.

2. An ironing table, comprising a board member, a pair of short legs, an elongated third leg, a pair of leg braces connected at one pair of end portions with said pair of legs, all of said legs and said leg braces being pivotally connected to the bottom portion 85 of the board near one end portion thereof, the third leg and the pair of legs being movable away from the board to extended diverged positions, a pair of board brace members pivotally connected to the bottom portion 90 of the board medially of its ends, said board brace members and said third leg crossing each other medially of their lengths when moved away from the board, the outer end portions of said board brace members 95 terminating adjacent the inner surfaces of the pair of legs and releasably bearing thereagainst, a yielding locking member non-slidably connected with the board brace members and releasably and slidably engageable 105 with the third leg to hold it in open position, and a transverse member carried by said third leg and engageable with said board brace members to hold the same in open position.

In testimony whereof, I affix my signature.
JOHN P. DORAU.
